UNITED STATES PATENT OFFICE.

HUGH MUNRO, OF GLASGOW, SCOTLAND.

DEVICE FOR CLEANING INTERDENTAL SPACES.

Application filed April 26, 1926, Serial No. 104,826, and in Great Britain October 17, 1925.

My invention relates to a device for cleaning the spaces between the teeth, and has for its object to provide one of a very simple and efficient nature.

In carrying out this invention, I provide a bar or bars in the form of a bow between the ends of which a thread is stretched, the thread being drawn to and fro between the teeth.

The limbs of the device are bent approximately in form of the letter **Z** near their ends—the middle bars of the **Z**'s being laid close together so that the limbs cross one another and in such a manner that when the uncrossed parts comprising the whole or the greater part of the limbs adjoining the crossing and between it and the loop of the bow are pressed together, the ends move apart and draw tight a thread attached to the tips of the bow.

The appliance also includes a receptacle for holding a supply of thread, means for fastening the thread and for cutting it.

In order that my invention may be properly understood and carried into effect, I have hereunto appended one sheet of drawings, of which Figure 1 is a front elevation, and Figure 2 a side view of the apparatus.

The bow consists of a bent bar 1 having its limbs 4, 4, extended parallel, or slightly inclined, to each other, and then crossed at 5. This crossing is effected by bending each limb towards the other through an angle of, or about 90° . After a short distance each limb is again bent through an angle of, or about 90° and extended parallel, or inclined at a small angle to the other or to its own previous direction, but not in the same line, each limb being thus shaped approximately in the form of the letter **Z**, the centre bar of the **Z** of one limb being close to that of the other.

In each tip 3 of the bow there is a slit 14 and around or partly around each tip is a groove 7^a, this groove being preferably right angled or undercut on that side nearest the end of the bow. The thread is coiled in a container 8, held in the loop 12 of the bow by means of flanges 13. Said container has a thread cutter 17. The limbs of the bow have thread fastening buttons 10.

From the container 8 the thread 2 is taken to the tips of the bow, and from the formation of the complete limbs it will be seen that the angle formed between the thread and each tip is 90° or approximating there-

to. It is laid in one slit, then coiled in the groove around that tip, and laid again in the same slit. The loose end is then laid in the slit in the other tip, coiled in the corresponding groove and laid again in the second slit. By now pressing together with the fingers on any part of the limbs 4, 4, between the crossing 5 and the looped part of the bar 1, the ends 3, 3, are moved apart and stretch the thread 2, attached to the tips. Thus held the thread is inserted between the teeth and drawn to and fro between them. A thread cutter 17 is formed on, or attached to, the container.

By thus bending the limbs of the bow approximately in the form of the letter **Z** and crossing them to form approximately the letter **H** many advantages are obtained. The operating part 2 of the thread being at, or about at right angles to the tips, its whole length is available for cleaning and the width from tip to tip is thus reduced to a minimum which makes for convenience when the tips are inserted into the mouth. By making the crossing 5 parallel to thread 2 the distance between them is reduced to a minimum and consequently the distance from the user's fingers (when holding the instrument on the other side of the crossing 5 from the thread 2) is also reduced to a minimum, thus affording him the maximum control over the manipulation of thread 2. Since the limbs are wide apart between crossing 5 and loop 1, ample travel of the tips can be obtained in order to take up any stretch of the thread 2 and to vary the longitudinal tension on it. As the limbs are preferably of small dimensions, (for convenience in the mouth), the disposal of the limbs, wide apart at the crossing, affords a secure grip to the user and adds to his control over the thread 2. The groove 7^a around or partly around the tips effectively prevents the thread slipping off the tips when the instrument is in use.

Claims.

1. Device for cleaning interdental spaces comprising a bow having a loop at one end and limbs extending from said loop substantially parallel to each other, the limbs thereafter being crossed by bending them towards one another, through an angle of substantially 90° , and then extended again substantially parallel to each other and to their previous directions, such that when any portion of the limbs between the loop and the cross-

ing are pressed together the ends move apart and exert longitudinal tension on a thread attached to the tips of the bow and at an angle to them of substantially 90°.

5. 2. Device for cleaning interdental spaces comprising a bow having a loop at one end and limbs extending from said loop substantially parallel to each other, the limbs thereafter being crossed by bending them towards each other through an angle of substantially 90°, and then extended again substantially parallel to each other and to their previous direction, such that when any portion of the limbs between the loop and the crossing are 10 pressed together the ends move apart and exert longitudinal tension on a thread attached to the tips of the bow and at an angle to them of substantially 90°, each end portion of said bow being provided with a slit in 15 and a groove around it.

3. Device for cleaning interdental spaces comprising a bow having a loop at one end and limbs extending from said loop substantially parallel to each other, the limbs thereafter being crossed by bending them towards each other through an angle of substantially 90° and then extended again substantially parallel to each other and to their previous direction, such that when any portion of the limbs between the loop and the crossing are 20 pressed together the ends move apart and exert longitudinal tension on a thread attached to the tips of the bow and at an angle of substantially 90°, each end portion of said bow being provided with a slit in, and a 25 groove around it, and a container for thread arranged in the loop of said bow.

In witness whereof I affix my signature.

HUGH MUNRO.
